[57] CLAIM

The ornamental design for a handle, as shown and described.

DESCRIPTION

FIG. 1 is a top, front perspective view of a handle embodying my new design;

FIG. 2 is a front elevational view thereof, the right side, left side, and rear elevational views being identical to the front elevational view shown;

FIG. 3 is a top plan view thereof; and,

FIG. 4 is a bottom plan view thereof.

The broken line representations of an escutcheon in FIGS. 1-4, and of mounting structure in FIG. 4, are for the purpose of illustration only, and form no part of the claimed design.
